(57) **CLAIM**

The ornamental design for an end cap for a curtain hanging system, as shown and described.

DESCRIPTION

FIG. 1 is a top front perspective view of an end cap for a curtain hanging system showing our new design in a position of use with exemplary environmental subject matter; FIG. 2 is a top front perspective view thereof, shown with the exemplary environment removed, to show aspects of the design not visible when combined;

FIG. 3 is a front view thereof;

FIG. 4 is a rear view thereof;

FIG. 5 is a side view thereof;

FIG. 6 is an opposite view thereof;

FIG. 7 is a top view thereof; and,

FIG. 8 is a rear view thereof.

The broken lines are shown for the purpose of illustrating both parts of the article as well as exemplary environmental subject matter. None of the broken lines form part of the claimed design.
